Primary Examiner — Lauren D McVey*Assistant Examiner* — Justin A Johnson(74) *Attorney, Agent, or Firm* — Lerner, David,
Littenberg, Krumholz & Mentlik, LLP(57) **CLAIM**

The ornamental design for a "therapeutic ear device," as shown and described.

DESCRIPTION

FIG. 1 is a Side view of the therapeutic ear device showing the new design in a closed position.

FIG. 2 is a Back view of the therapeutic ear device shown in FIG. 1;

FIG. 3 is a Front view of the therapeutic ear device shown in FIG. 1;

FIG. 4 is a Top view of the therapeutic ear device shown in FIG. 1;

FIG. 5 is a Bottom view of the therapeutic ear device shown in FIG. 1;

FIG. 6 is an Isometric Back view of the therapeutic ear device shown in FIG. 1; and,

FIG. 7 is an Isometric Side view of the therapeutic ear device shown in FIG. 1 with a front section in the open position. The broken lines immediately adjacent to the claim depict the bounds of the claimed design, while all other broken lines are directed to environment. The broken lines form no part of the claimed design.
